[57] CLAIM

The ornamental design for an interconnecting toy tile, as shown and described.

DESCRIPTION

FIG. 1 is a top front and left side perspective view of a interconnecting toy tile showing my new design;

FIG. 2 is a front elevational view thereof, the side opposite being a mirror image;

FIG. 3 is left side elevational view thereof;

FIG. 4 is a top plan view thereof;

FIG. 5 is a right side elevational view thereof; and,

FIG. 6 is a bottom plan view thereof.

The rear view of the toy tile of FIG. 1A is a mirror image of the front, elevational view depicted in FIG. 1B. The rear view of the interconnecting toy tile of FIG. 2A is a mirror image of the front, elevational view depicted in FIG. 2B. The rear view of the interconnecting toy tile of FIG. 3A is a mirror image of the front, elevational view depicted in FIG. 3B. The rear view of the toy tile of FIG. 4A is a mirror image of the front, elevational view depicted in FIG. 4B. The rear view of the toy tile of FIG. 5A is a mirror image of the front, elevational view depicted in FIG. 5B. The rear view of the toy tile of FIG. 6A is a mirror image of the front, elevational view depicted in FIG. 6B.
